COMBINED KEYBOARD TAPE TRANSMITTER

Albert H. Reiber, Evanston, Ill., assignor to Teletype Corporation, Chicago, Ill., a corporation of Delaware

Application November 9, 1939, Serial No. 303,518

10 Claims. (Cl. 178—17)

This invention relates to telegraph transmitters and more particularly to telegraph transmitters controllable either from a manually operated keyboard or signal control indicia included in a strip.

An object of the invention is the provision of an extremely simple and very compact apparatus for transmission of telegraph signals either from a keyboard or a control strip.

A feature of the invention is the provision of selectively operative elements controllable either from a keyboard or a control strip for the transmission of code combinations of signal impulses.

The above and other objects and features of the invention are attained by the provision of a transmitting cam drum released cyclically for keyboard transmission and operated continuously for strip or tape transmission for operating successively a plurality of contact control levers, as determined either by the setting of code bars through the depression of key levers or by elements positioned in accordance with the signal perforations or indicia in the strip or tape, depending upon whether the apparatus is conditioned for keyboard or tape transmission. Conditioning the apparatus for keyboard or tape transmission is established by mechanism having two operative positions. In one of such positions the keyboard is free to be operated and the elements positioned in accordance with a signal perforation or indicia are rendered ineffective, while in the other of its positions, the keyboard is blocked against operation and the specified elements are allowed to assume positions to control the position of contact control levers by the signal perforations or indicia to control effectively the signal impulses transmitted to the line conductor with which the apparatus may be connected.

Specifically, conditioning the apparatus for keyboard or tape operation is controlled by a system of levers. When in one position, operation of the key levers is prevented and when in another position, the elements responsive to the tape perforations are moved free of the contact control levers and the mechanism for advancing the tape step by step is rendered inert. In addition, for the respective positions, the transmitting cam drum will rotate either intermittently or continuously. When in the keyboard position, tape operation cannot be resumed until the key levers are blocked and the transmitting cam drum stop mechanism is in a position for arresting the transmitting cam drum at the completion of its cycle of rotation. The transmitting cam

drum may thereafter be released for continuous rotation to effect transmission of signal impulses, as determined by the signal perforations or indicia in the control strip. Arrestment of the transmitting cam drum when the mechanism is in the tape transmission position may also be effected.

A more detailed understanding of the invention may be obtained from the following description, taken in conjunction with the accompanying drawings, wherein:

Fig. 1 is a plan view of apparatus embodying the present invention;

Fig. 2 is a partial sectional elevational view of the apparatus shown in Fig. 1;

Fig. 3 is a sectional view taken substantially along the broken line 3—3 of Fig. 1;

Fig. 4 is an end elevational view partly in section of the apparatus shown in Fig. 1;

Fig. 5 is a view taken substantially on the broken line 5—5 of Fig. 1;

Fig. 6 is a partial sectional view showing certain elements in their respective operating positions; and

Fig. 7 is a circuit diagram showing the electrical connections for the apparatus.

According to its preferred embodiment, the apparatus has a cast metal base or frame 12 provided with a front extension 13. Key levers 14 are arranged within the upper portion of the base or frame 12 have their rear ends in engagement with a common pivot rod 15 carried by lugs suitably supported by the base or frame 12. The forward ends of the key levers extend through the slots of a comb bar 16 and are upturned to support keys 17. A bail 18 pivoted on the forward extension 13 carries a space bar (not shown). The key levers and the space bar are held in their normal position by suitable springs.

A set of five permutation bars 22, 23, 24, 25, and 26 extend transversely below the key levers, the ends of the bars being guided in slots in oppositely disposed brackets 19 fixed within the base 12 and being supported on antifriction rollers 20. In addition to the permutation bars 22 to 26, inclusive, is a bar 21 which has two alternative positions. In one of such positions the key levers 14 are free to be moved, whereas in its other position movement of the key levers 14 is prevented; that is, bar 21 serves to free or block the movement of key levers 14.

Each permutation bar 22 to 26, inclusive, is free to move longitudinally to either one of two positions and each bar has cam lugs 27 having oppositely inclined faces, one such face being

provided on each bar for each of the key levers 14 so that each bar is adapted to be moved to its right-hand position by some of the keys and to its opposite left-hand position by the other keys. Accordingly, the keys act to set the permutation bars 22 to 26, inclusive, in different combinations.

Intermediate the ends of each of the permutation bars 22-26 are pins 28 and 29 which are spaced to receive the lower end of a corresponding selecting finger 30. The five selecting fingers 30 extend upwardly through an opening in the base 12 and are mounted upon a common pivotal support 31 extending between two suitably arranged brackets fastened to base 12. The fingers 30 control a set of switch control bell crank levers 32 mounted upon a horizontal pivot shaft 33 carried by uprights 34 and 35. Each selecting finger 30 has a hooked lug 38 at its upper end which, as the associated permutation bar is shifted, is moved into and out of the position above the end of the horizontal arm of the associated bell crank lever 32. The fingers 30 and the bell crank levers 32 are held in proper position by spacing washers on the pivot shafts 31 and 33, respectively, and preferably also a guide comb bar 39 is provided for the horizontal arms of the bell crank levers 32, as is shown in Fig. 3.

In addition to the bell crank levers 32 there is a sixth bell crank lever 40 which is not controlled by a selecting finger 30 or one of the permutation bars 22-26, but is, as will be explained later, operated invariably for each cycle of operation of the apparatus for transmitting a start impulse.

Each bell crank lever 32, which is equally true of bell crank lever 40, has a hook 41 at its upper end which engages the insulated upper end of a spring contact 42 and each of the latter cooperates with a spring contact 43, the pairs of contact springs being mounted upon but insulated from a supporting bar 36 carried by uprights 34 and 35. Each spring contact 42 tends to engage its associated contact spring 43 and also serves to hold a lug (not shown) on the horizontal portion of each of the bell crank levers 32 in engagement with the surface of a cylindrical cam 44, the latter constituting a part of a sleeve or drum 45 and extending over the horizontal arms of the bell crank levers 32 and 40. The cam drum 45 is provided with a helical series of slots which, as the cam sleeve 45 is rotated, successively pass over the lugs (not shown) on the horizontal arm of the bell crank levers 32 and 40. As the corresponding recess passes over one of the lugs, the associated switch contact spring 42 is allowed to engage its associated contact spring 43 to complete an electrical circuit through the respective contact springs under the control of the corresponding bell crank lever 32.

Cam sleeve 45 is mounted on a shaft 46 which is journaled at its rear end in a bearing mounted in bracket 48 and at its forward end in a bearing mounted in the front upright 34. Cam sleeve 45 is mounted loosely on shaft 46; that is, shaft 46 may be rotated continuously while cam sleeve 45 is being held against rotation.

The cam sleeve 45 has secured to it a collar 49, a portion of which is serrated and normally urged along the shaft 46 to the right, as viewed in Fig. 4, by the action of a spring 50. Secured to the shaft 46 and arranged to cooperate with collar 49 is a correspondingly machined collar 51. Shaft 46 is connected to a source of driving power through a gear 52 in such a manner

that it is driven continuously, but due to the arrangement of collars 49 and 51, which constitute a clutch between shaft 46 and cam sleeve 45, the latter may be selectively rotated.

Spring 50, as previously described, tends to move collar 49 along shaft 46 and into engagement with collar 51, but this action of spring 50 is normally prevented, by means of a pivoted arm 53, Fig. 4, which has a portion thereof spring-10 urged into the path of a shoulder 54 formed on collar 49. Shoulder 54 is also formed with a gradual cam surface so that as the collar 49 rotates, it will cooperate with the associated portion of the stop arm 53 and cause the collar 49 to be moved along the shaft 46 against the action of spring 50 to disengage the serrated portions of the collars 49 and 51 and stop collar 49 with its associated cam sleeve 45.

Arm 53 has a horizontal portion 55 which is operatively associated with one arm of a T-shaped lever 56, the depending arm of which is pointed and is in the path of a shoulder 57 formed in a member 58, Fig. 4. The member 58 is secured to a universal bail 59 which is rotatably mounted on studs 60 suitably secured to brackets in base 12. A spring, one end of which is fastened to member 58 and the other end secured to a fixed spring post, urges the member 58 to the position shown in Fig. 4, or a position 30 in alignment with the depending arm of T-lever 56.

When the universal bail 59 is operated, which will occur upon the depression of any of the key levers 14, member 58 will be moved to the left, 35 as viewed in Fig. 4, against the action of its spring and the shoulder 57 will engage the pointed end of the T-shaped lever 56 and cause stop arm 53 to be moved through the depression of portion 55, out of engagement with shoulder 54 of collar 49. Under these conditions, spring 50 urges collar 49 to the right, as viewed in Fig. 4, and the serrated portions of the collars 49 and 51 are brought into engagement and power from shaft 46 is communicated thereto to rotate cam sleeve or drum 45 with its cams 44. When the cam sleeve or drum 45 approaches the end of its cycle of rotation, the cam surface preceding the shoulder 54 is effective upon stop arm 53, which has, upon the restoration of bail 59, returned by the action of its spring to the position shown in Fig. 4, to move collar 49 against the action of spring 50 and effect the disengagement of the serrated portion of collar 49 from that of collar 51.

Each of the selecting fingers 30 is provided at its upper end with upwardly projecting portions 61, Fig. 3, having beveled upper edges which cooperate with a beveled edge rib on a locking bail 62. The locking bail 62 is pivotally mounted on suitable uprights and a spring 63 tends to depress the locking bail 62 and hold a roller 64 secured to an arm integral with locking bail 62 in contact with a lug 65 on cam drum or sleeve 45 when the cam drum is in its arrested position. Shortly after the cam drum 45 is released for rotation and the lug 65 has been moved free of the roller 64 on the arm of locking bail 62, the locking bail under the action of its spring 63 is moved about its pivot to bring its beveled rib 70 into cooperation with the beveled portions of projections 61 and consequently lock the selecting fingers 30 in the position in which they were set due to the operation of the permutation bars 22-26. With such a construction, the permutation bars cannot be operated during the cycle

of rotation of cam drum 45 or until locking bail 62 is moved by lug 65 to free the beveled rib from the beveled portions of the projections 61 on the selecting fingers 30.

There is also mounted on cam drum 45 a cam 66, Fig. 1, which cooperates with and operates invariably for each cycle of rotation of cam drum 45 bell crank lever 40 to cause correspondingly the opening of its associated contact springs 42 and 43, thereby to open the connected line circuit and transmit what is referred to as a start impulse. Consequently, at the beginning of each cycle of rotation of cam drum 45, cam 66 operates its bell crank lever 40 to open contacts 42 and 43 to transmit a start impulse. Following the transmission of the start impulse, cams 44 also carried by cam drum 45, are effective successively to control the operation of the associated bell crank levers 32 in accordance with the position of the selectable fingers 30, as previously set in response to the operation of the permutation bars 22—26, inclusive.

As cam drum 45 nears the end of its cycle of rotation, stop arm 53 is effective to cam collar 49 against the action of its spring 50 sufficiently to effect its disengagement from collar 51 and arrest rotation of cam drum 45.

Also mounted on cam drum 45 is a shoulder or cam 69, Fig. 1, which cooperates with a roller 70 secured near the free end of an arm 71 pivoted to end upright 35 and urged about its pivot by a spring secured between its free end and a fixed spring post secured to the back face of upright 35, as viewed in Fig. 1. Due to the cooperation of roller 70 with the periphery of cam 69 and particularly the recessed portion thereof, singeing or chattering of the clutch comprising the collars 49 and 51 is prevented during periods of arrestment of driven portion 49 and the initial rotation of cam drum 45. Since spring 50 opposes the disengagement of collars 49 and 51, a slight torsional bias may be required to establish and maintain a gap between the clutch portions after bare disengagement has occurred, it being understood that disengagement and separation of the clutch portions results solely from rotation of clutch throwout cam surface on shoulder 54 against the upper end of stop arm 53. Cooperation of roller 69 with the descending slope of the recess in the periphery of cam 69 provides the desired torsional bias.

Control of the initial rotation of cam drum 45 is important because, as previously described, its cam 66 controls bell crank lever 40 to impress upon the telegraph line the start impulse, the effect of which is to set in operation the telegraph printer connected to the telegraph line. If cam drum 45 should be permitted to be rotated far enough to initiate the start impulse before firm engagement of the clutch portions is established as, for example, by frictional engagement of the tips of the clutch teeth on collars 49 and 51, distortion of some portion of the signal combination to be transmitted is likely to result, due to the subsequent slipping of the clutch portions into firm engagement and accompanying variation in the velocity of cam drum 45. The immediate establishment of firm engagement between the clutch portions may be assured by exerting upon the driven collar 49 a drag sufficient to resist rotation due to frictional engagement between the teeth of collars 49 and 51. The desired drag is furnished by engagement of roller 70 with the periphery of cam 69 and particularly with the sharp ascend-

ing slope of the recess therein which roller 70 encounters substantially immediately upon the tripping of stop arm 53 and the movement of its upper end free of shoulder 54.

5 The description to this point applies specifically to the operation of the apparatus in accordance with the depression of key levers 14 and the transmission of signal impulses in accordance with such depressions through the cyclic 10 rotation of cam drum 45. The invention also embodies apparatus for the transmission of signal impulses according to perforations in a previously perforated tape which may be prepared either through the operation of a keyboard perforator or a re-perforator which responds to code combinations of signal impulses.

The perforated tape includes transverse rows of perforations arranged permutably in accordance with the prearranged code and is utilized 20 to control permutably the setting of a plurality of pivoted fingers 73, one individual to each possible perforation appearing in a transverse row of perforated tape 74. As disclosed in Figs. 1 and 3, the fingers 73 are pivotally mounted on a shaft 75 which is supported by ears formed in vertically projecting plates 76 and 77 secured to the upper surface of base 12. Fingers 73 are normally urged in a counterclockwise direction about shaft 75 by a spring 78 (Fig. 3) which has one end secured to a depending arm 79 and its other end secured to a fixed spring support 80, there being a spring 78 individual to each of the five selecting fingers 73. Each of the fingers may be operated individually. Each of the fingers 73 also has horizontally projecting arms 81 and 82, the former of which carries near its end a pin 83 arranged to pass through an aperture 84 individual thereto formed in horizontal plate 85, which is integral with plates 76 and 77, to 30 sense the presence or absence of a perforation in tape 74 which, as will be later described, will be advanced step by step to bring its successive transverse rows of perforations in alignment with pins 83 individual to the arm 81 of each of 35 the selecting fingers 73. Arm 82 of each of the fingers 73 lies adjacent the upper end of its selecting finger 30 which, as shown in Fig. 3, is notched at 86 to receive the free end of arm 82 of its selectable finger 73, depending upon 40 whether its pin 83 has sensed a perforation in tape 74. For example, if pin 83 senses a perforation in tape 74, spring 78 rotates finger 73 sufficiently to bring its arm 82 in alignment with slot 86 in the upper end of its corresponding selecting finger 30 so that, as will be described in detail later, such selecting finger 30 is permitted to move about its pivot 31 sufficiently to free its corresponding bell crank lever 32 and permit the closure of contact springs 42 and 43.

50 Tape 74, intermediate certain of the code perforations therein, includes feed perforations arranged to be engaged by pins mounted in the periphery of a pin feed wheel 90, Fig. 3, which is secured to a shaft 91 journaled in plates 76 and 77. As pin wheel 90 rotates, its pins engage the feed perforations in tape 74 and thereby advance the tape past the pins 83 carried by the arms 81 of selecting fingers 73. Rotation of shaft 91 and correspondingly pin wheel 90 is achieved through a ratchet wheel 92, Fig. 5, which is also secured to shaft 91. Cooperating with the teeth of ratchet wheel 92 is a feed pawl 93 and a holding pawl 94 (Fig. 5) which is pivoted at 95 and which is urged into engagement with the periphery of ratchet wheel 92 by a spring 96 which

has one end secured to an arm of holding pawl 94 and its other end secured to a spring post mounted in the inner face of plate 77. Pawl 93 is rotatably secured to an arm 97 of a U-shaped member 98 pivoted on shaft 75 and having an arm 99 fastened to one end of a spring 100 and engageable with a post 101 to limit the travel of member 98 and consequently limit the movement of pawl 93.

As shown in Fig. 5, member 98 has an arm 102 positioned above plate 85. When this arm 102 is depressed, member 98 will be rotated about its pivot shaft 75 in a clock-wise direction to draw pawl 93 downwardly and thus effect the rotation of ratchet wheel 92. Due to the fact that ratchet wheel 92 is secured to shaft 91 to which pin wheel 90 is also secured, pin wheel 90 will be advanced step by step for each operation of member 98 through operation of arm 102 to advance tape 74 correspondingly. Through such operation the tape 74 may be advanced step by step through manual operation of arm 102 and member 98.

Member 98 also has an arm 103 to which is secured a member 104 which carries at its free end a cam roller 105 arranged to cooperate with a cam 106 integral with cam drum 45. For each rotation of cam 106 and provided roller 105 is in engagement with its periphery, member 104 will be rotated to permit rotation of member 98 under the action of its spring 100, whereupon pawl 93 is retracted to a position where its hook portion engages the next succeeding tooth on ratchet wheel 92. Upon the continued rotation of cam 106, member 98 will be rotated in a clockwise direction against the action of its spring 100 and pawl 93 will be moved downwardly, as viewed in Fig. 5, to rotate ratchet wheel 92 a distance equal to the distance between adjacent teeth on its periphery. For each such operation, pin wheel 90 is rotated and tape 74 advanced correspondingly. Ratchet wheel 92 is, of course, held in its advanced position due to the cooperation of holding pawl 94 with its periphery.

To facilitate insertion of tape 74 preparatory to transmission in accordance with the transverse rows of perforations therein, mechanism is provided for withdrawing stepping pawl 93 and holding pawl 94 from engagement with the periphery of ratchet wheel 92. This mechanism includes a system of levers indicated generally by the reference character 110, Fig. 5, pivotally mounted on rod 111 extending between plates 76 and 77. The lever system 110 has arms 112 and 113, the former of which engages stepping pawl 93 and the latter of which engages holding pawl 94 when the lever system 110 is rotated in a clockwise direction about rod 111, as viewed in Fig. 5. Rotation of lever system 110 against the action of a spring 114, which has an end secured to an arm of lever system 110, is effected by an arm 115 provided with a portion 116 which normally lies substantially in an oblique plane. When portion 116 is manually depressed, arms 112 and 113 are rotated clockwise, as viewed in Fig. 5, to remove stepping pawl 93 and holding pawl 94 from engagement with ratchet wheel 92. Under such circumstances pin wheel 90 is free to rotate so that the tape 74 may be freely inserted to bring the first transverse row of perforations in alignment with the pins 83 of the selectable fingers 13.

To further facilitate insertion of tape 74 for transmission, a plate 118 of suitable transparent material is secured to the upper surface of plate

85 and has its left-hand end, as viewed in Fig. 3, curved to conform substantially with the curvature of a metal plate 119 secured also to plate 85 to direct the course of the tape 74 as it passes from the sensing position. Plate 85 has a portion of its upper surface recessed slightly to form a groove to receive tape 74. By securing plate 118 to the upper surface of plate 85, a channel is provided for the tape.

By having plate 118 of transparent material, an operator in inserting the tape, can observe exactly how far the tape should be inserted to bring the first transverse row of perforations in alignment with the pins 83 for the purpose of sensing and the transmission of corresponding signal impulses. With plate 118 made from opaque material, the operator is unable to determine the exact position of insertion of tape 74 and consequently the tape is inserted to a position where the first transverse row of perforations is to the right, as viewed in Fig. 3, of the pins 83. It therefore becomes necessary to advance the tape step by step until the first transverse row of perforations is in a sensing position, when signal transmission will be commenced. However, during such preliminary advancement of the tape, the cam drum 45 will be rotating and a blank signal for each cycle of rotation will be transmitted until the first transverse row of perforations in tape 74 is brought to a sensing position. Such an arrangement results in an appreciable loss of line time. With the plate 118 of transparent material, the operator can locate the first transverse row of perforations in a sensing position when transmission may be initiated without any loss of line time and without the transmission of any blank signals.

As disclosed in Fig. 1, plate 118 is cut away as indicated by the numeral 120 to receive a finger 40 of the operator and thus further facilitate insertion of tape 74 when pin wheel 90 will be rotated freely.

When the apparatus is being used for direct keyboard transmission, it is necessary to rotate 45 selectable fingers 13 against the tension of their springs 78 sufficiently to move the free end of arm 82 out of the path of the upper end of its selecting finger 30. Correspondingly, when the apparatus is to be used for transmitting signals from a perforated tape such as 74, it is necessary to condition the apparatus for such operation and to preclude the operation of the key levers 14. Also, because the same cam drum 45 which transmits the signal impulses in accordance with the operation of the key levers 14 and the setting of 50 the permutation bars is utilized for the transmission of impulses in accordance with the transverse rows of perforations in tape 74, it is necessary to selectively control the starting and stopping of the cam drum 45 when a change is effected from one type of operation to the other type of operation. To accomplish these results, the invention embodies certain mechanisms 55 which will now be described.

Each of the permutation bars 22 to 26, inclusive, is notched near its right-hand end, as viewed in Figs. 3 and 5, to receive the ball end of a lever 125 pivoted on a rod 126 extending between plates 76 and 77 and fastened to one end of a spring 127 which has its other end, as shown in Fig. 3, loosely secured to a bail 128 pivotally mounted on pivot pins 130 fastened to plates 76 and 77. For direct keyboard operation, levers 125, there being such a lever individual to each 70 of the permutation bars 22-26, are in the posi-

tion shown in Figs. 3 and 5, wherein spring 127, due to the loose connection of its end with bail 128, does not subject the permutation bars 22-26 to any additional load when the key levers 14 are depressed. When in such position, the permutation bars 22-26 may be operated freely since member 144, as later described, is held depressed by lever 132.

Secured to bail 128 is one end of a link 131 which has its other end secured to a lever 132 also pivoted on rod 126. As shown in Fig. 3, link 131 has a curved portion to clear an eccentric 133 mounted on shaft 111 journaled as previously described in plates 76 and 77, which also constitutes a pivot shaft for lever system 110. Secured to the forward end of shaft 111 is a collar 134 provided with an arm 135, Fig. 1, a cam surface 136, Fig. 2, and a shoulder 137, Figs. 1 and 2. Also secured to shaft 111 is a finger 138 engageable with pins 139 and 140 mounted on the outer face of plate 76 to limit the rotation of shaft 111 and correspondingly collar 134.

As shown in Figs. 1 and 3, lever 132 has a horizontal bail portion 142 and an arm 143. Bail 142 cooperates with each of the arms 79 of the selectable fingers 73 to rotate, under certain conditions, the selectable fingers 73 against the action of their spring 78 to move their arms 82 free of the upper end of selectable fingers 30. Arm 143 of lever 132 cooperates with the surface of inclined member 144 integral with a U-shaped bail 145 pivoted on rod 33 and having extensions 146 to which one end of springs 147 are secured, the other end being secured to a fixed spring support on guide comb 39 to hold cam rollers 148, only one of which is shown, mounted in bail 145 in contact with cams 149 and 165 also secured to cam drum 45.

Eccentric 133 cooperates with surfaces of link 131 to move the link either to the right or left, as viewed in Fig. 3. When moved to the left due to the clockwise rotation of eccentric 133, as viewed in Fig. 3, lever 132 is rotated about its pivot 126 to move selectable fingers 73 to a position where pins 83 are below plate 85 and arm 82 is free of the upper end of its selectable finger 30 and bail 145 is rotated against the action of its spring 147 to remove roller 148 from engagement with cam 149 and allow selectable fingers 30 to follow the movement of permutation bars 22-26. Movement of link 131 to the left, as viewed in Fig. 3, also rotates bail 128 about its pivots in a clockwise direction and frees springs 127 of tension, so that the permutation bars 22-26 are relieved of any effect of springs 127.

When eccentric 133 is rotated counterclockwise, as viewed in Fig. 3, through rotation of collar 134 upon the operation of arm 135, link 131 will be moved to the right, rotating bail 128 in a counterclockwise direction and, through springs 127 and levers 125, move permutation bars 22-26 to the left, as viewed in Fig. 3, or to the all-marking position. The specified movement of link 131 causes lever 132 to be rotated in a clockwise direction to move bail 142 free of arm 79 of each of the selectable fingers 73 to move arm 143 out of engagement with projection 144 of bail 145 to allow spring 147 to rotate bail 145 to bring roller 148 into engagement with cam 149 and move the arm 82 of each of the selectable fingers 73 to a position above the slot 86 in each of the selecting fingers 30, because when bail 142 was rotated in a clockwise direction, the spring 78 individual to selectable fingers 73 rotated the fingers to a position where arm 92 was in align-

ment with its corresponding slot 86 in the selecting finger 30. Due to the rotation of lever 132, an extension of arm 143 engages a surface of locking bail 62 to rotate the bail against the action of its spring 63 to remove its beveled rib free of the beveled ends 61 of selecting fingers 30 and roller 64 free of lug 65.

The apparatus, when used for direct keyboard operation, is arranged such that the permutation bars 22-26 remain in their set position until a change is occasioned through the depression of another key lever 14. Consequently, the selecting fingers 30 remain in their set position, either marking or spacing position. When eccentric 133 is rotated counterclockwise, as viewed in Fig. 3, to permit elevation of bail 145, the bail engages surface 150 near the upper end of each of the selecting fingers 30 and cams each of the selecting fingers counterclockwise to a position where its hook 38 lies in the path of the horizontal arm of its associated bell crank lever 32, in which position the contacts 42 and 43 are maintained open, except for the contacts individual to bell crank lever 40, which is controlled by cam 66.

When conditioning the apparatus for tape operation, it is essential that the key levers 14 be locked against operation. To achieve this result, bar 21 is movable to the left against the tension of a spring 151, which has one end secured to a projection on the lower edge of bar 21 and the other end secured to a fixed spring post on base 12, upon movement of a lever 152 which has one end in engagement with the right-hand end of bar 21 and the other end engageable by a cam 136 formed in collar 134. When collar 134 is rotated to condition the apparatus for tape operation, cam 136 engages the upper arm of lever 152 to rotate the lever clockwise about its pivot and move bar 21 against the action of its spring 151 to the left, as viewed in Fig. 2, whereupon a projection on the upper edge of bar 21 is moved into the path of each of the key levers 14. Under such conditions, none of the key levers 14 can be depressed, which insures against operation of the key levers 14 during tape transmission, for if a key lever 14 was depressed during tape transmission and provided the code bars 22-26 are operated, the signals intended to be transmitted in accordance with the perforations in the tape 74 would be mutilated.

With the apparatus in the position just described, operation from the perforated tape 74 may be initiated. Initiation of tape operation is effected through the withdrawal of stop arm 53 from the path of shoulder 54 of collar 49 to permit spring 50 to move collar 49 into engagement with collar 51, which rotates continuously. To achieve this result, T-shaped lever 56 is arranged to be operated by rod 153, which is slidably mounted in suitable supports and which carries near its forward end, as viewed in Fig. 1, adjustable nuts 154 engageable by a projection 155 formed in the vertical edge of bar 156 which is pivoted on a shoulder screw 157 secured to the upper face of base 12 and which is rotatable by a lever 158. Lever 158 has two positions, identified as a stop position and a start position. When in its stop position, projection 155 of bar 156 allows a spring 160 (Fig. 2), which has one end secured to a spring post and the other end secured to an arm 161 (Fig. 4), pivoted on a rod 162 having a vertically extending arm 163, to move through arm 163 and nuts 154, rod 153 to a position where it is out of engagement with

T-lever 56. When lever 158 is rotated to its start position, bar 156, through its projection 155, moves rod 153 forward, as viewed in Fig. 1, against the tension of spring 160, whereupon T-lever 56 is operated to move stop arm 53 out of the path of lug 54 formed on collar 49 to permit spring 50 to move collar 49 into engagement with continuously rotating collar 51. Bar 156 is held in its two positions by a detent bar 164 which is mounted on the upper surface of base 12.

The free end of bar 156 is adapted to engage shoulder 137 formed in the periphery of collar 134 when lever 158 is in its start position, whereupon cam drum 45 rotates continuously. When bar 156 is so positioned, arm 135 and collar 134 cannot be rotated to change the apparatus from tape operation to direct keyboard operation. Consequently, in order to permit a change from tape operation to direct keyboard operation, it is necessary to rotate lever 158 to its stop position wherein rod 153 will be restored by spring 160 to a position out of engagement with T-lever 56, whereupon stop arm 53 is rotated about its pivot to a position where its upper end lies in the path of stop lug 54 to move collar 49 out of engagement with collar 51 at the completion of a signaling cycle.

When lever 158 is rotated to its start position, cam drum 45 rotates continuously. For each cycle of rotation of cam drum 45, cam 163 operates bell crank lever 40 to operate its contact springs 42 and 43 to transmit to the connected line a start impulse, and cams 149 and 163, through rollers 148, permit and operate bail 145. During the stop impulse, bail 145 is moved by its spring 147 to a position where the selecting fingers 30 are moved to a position where their hook 38 lies in the path of the horizontal arm of bell crank lever 32 and arm 82 of selectable fingers 73 is in alignment with the upper end of its corresponding selecting finger 30. As cam 149 rotates, and during the transmission of the start impulse, bail 145 is moved downwardly to permit rotation of selecting fingers 73 by the action of their spring 78 to a position where the pins 83 sense the respective signal areas of tape 74. In the up position of bail 145, arm 82 of sensing fingers 73 are in line with associated projections on lock levers 30, while in the down position of bail 145, arm 82 of fingers 73 are in line with notch 86 in lever 30 unless finger 73 is blocked by blank tape. If a pin 83 encounters an unperforated area in tape 74, rotation of its selectable finger 73 is limited. However, if a pin 83 passes through a perforation in tape 74, its selectable finger 73 by its spring 78 is rotated about pivot 75 to position its arm 82 in alignment with slot 26 formed in the upper end of its corresponding selecting finger 30. In its other position or the position wherein pin 83 encounters an unperforated area of tape 74, arm 82 lies in the path of the upper end of its corresponding selecting finger 30.

As bail 145 continues its downward movement and before the end of the start impulse, selecting fingers 30 are free to be moved by their individual spring 127, as determined by the position of arm 82 of its selectable finger 73. If arm 82 is in alignment with notch 86, then its corresponding selecting finger 30, by the action of its spring 127, is moved to a position where hook 38 is free of the horizontal arm of its corresponding bell crank lever 32. Now, as its corresponding cam 44 becomes effective, contact springs 42 and 43

will close for the transmission to the connected line circuit of a corresponding impulse. However, if arm 82 is held in its upper position, its end engages the upper end of its corresponding 5 selecting finger 30 and does not permit movement of its selecting finger 30 sufficiently to free hook 38 from the horizontal arm of bell crank lever 32. Consequently, its corresponding contact springs 42 and 43 will not be closed when the recess of its cam 44 is aligned with the lug of its bell crank 32.

For each rotation of cam drum 45, cam 106 rotates arm 104 through roller 105 to move stepping pawl 93 to engage the next succeeding tooth, 15 Fig. 5, and rotate ratchet wheel 92 a distance equal to the space between adjacent teeth and correspondingly rotate shaft 91 and pin wheel 90 to advance tape 74 to present the next transverse row of perforations in alignment with pins 20 83. Such advancement, however, does not occur until bail 145 has been moved to its extreme uppermost position by the action of spring 147 as permitted by cam 149, wherein pin 83 of each of the selectable fingers 73 is positioned free of tape 74, as shown in Fig. 3.

If it is desired to advance the tape 74 step by step under manual control, lever 158 is operated to its stop position wherein arm 53 will be positioned in alignment with stop lug 54 on collar 49. 30 Through the operation of arm 163, rod 153 is moved to rotate T-lever 56 to move stop arm 53 free of stop lug 54. If arm 163 is held in such position, cam drum 45 will rotate continuously and transmission will continue from perforated 35 tape 74. However, if it is restored immediately after its operation, cam drum 45 will make but a single cycle. Such operation can, of course, be continued by the momentary operation of arm 163. In this way the tape 74 may be advanced 40 slowly to bring a particular area in alignment with the sensing pins 83 and its exact position determined due to the transparent plate 118.

If, when the arm 135 is in the tape position and the lever 158 is in the start position it is 45 desired to change from tape operation to direct keyboard operation, lever 158 first must be rotated to its stop position wherein the free end of bar 156 is moved free of shoulder 137 of collar 134, when collar 134, through arm 135, may be 50 rotated to its direct keyboard position, wherein projection 138 contacts stop lug 139. Selecting fingers 73 are now in a position where pins 83 are below plate 85, and stepping pawl 93 is held against movement even though cam 106 rotates 55 for each key lever depression. Key levers 14 are free for operation because lever 152 is free to be moved to the position shown in Fig. 2 by the action of spring 151 which moves bar 21 to a position where its projections lie out of the path 60 of key levers 14.

The keyboard transmitter and the tape transmitter previously described are associated with and operatively connected to a receiving printer indicated generally by the reference character 65 170 which may be of the type and form disclosed in copending application Serial No. 77,796 of Albert H. Reiber and copending application Serial No. 204,038 of Carl A. Levin, wherein description will be found of apparatus for performing 70 selective functions. Included with such functions is the function of operating a pair of contacts which serve, when closed, to short circuit contact springs 42 and 43 and thus preclude the transmission of signal impulses to the connected line circuit upon the rotation of cam drum 45.

Closure of the specified contacts is under the control of what is usually referred to as a function bar; that is, a bar which is selected upon the permitted setting of the permutation bars for performing a particular function.

As disclosed in the cited copending applications there are a plurality of function bars. Corresponding function bars are indicated in the present specification generally by the reference character 171, which embody a particular function bar 172. The function bars 171 respond to a particular setting of the code discs of the receiving printer disclosed in the cited copending applications and, when selected, function to perform its particular operation.

A function lever 173 pivoted at 174 is biased in clockwise direction by a tension spring 175 and normally occupies the solid line position shown in Fig. 1. Lever 173 has a contact operating extension which cooperates with a pair of electrical contacts 176 which are normally open but which, when closed, establish a short circuit for contacts 42 and 43 of the transmitter. When contacts 176 are closed, transmission of impulses to the connected line circuit is precluded.

Rocking of lever 173 to its extreme counterclockwise position is accomplished by function bar 172 which has its free end arranged to cooperate with a latch lug 177 on function bar 173. When function lever 172 is selected and operated, it will be held in such position by latching lug 177. Function lever 173 falls in against the left-hand side of function bar 172 and holds it from returning to its extreme clockwise position at the end of the function testing operation, as fully described in the aforementioned copending applications. Upon the rearward reciprocation of function bar 172, lever 173 will be rotated to the dotted line position shown in Fig. 1 and thus cause the closure of contacts 176 and the establishment of a short circuit for contacts 42 and 43.

A bracket 178 suitably secured to a bracket mounted on the base 12 supports a latch lever 179 which is biased in counterclockwise direction by tension spring 180. At its right-hand end, as viewed in Fig. 4, lever 179 is step-cut to provide a shoulder for engaging lever 173 near its right-hand end, as viewed in Fig. 1, to block the return of lever 173 and thus the opening of contacts 176.

At the left-hand end, as viewed in Fig. 4, lever 179 has a portion 181 sloping obliquely downwardly. In the previous description the key levers of the keyboard transmitted were indicated by the reference character 14. A particular key lever which initiates the generation of a signal combination that will be hereinafter specifically identified, is indicated in Fig. 4 by reference numeral 182 which, like the key levers 14, is pivoted on pivot rod 15. Key lever 182 has secured thereto adjacent to the point at which it is pivotally mounted a clamp 183 which includes reverted fingers 184 fitted over one edge of key lever 182 and clamping screw 185 engaging the other edge of the same key lever and drawing reverted fingers 184 firmly into engagement with the first-mentioned edge. Clamp 183 has secured thereto or integral therewith an arm 186 which extends rearwardly of base 12 and arm 186 has a vertically directed portion 187 which emerges from base 12 to an aperture at the rear thereof and terminates beneath lever 179 adjacent to the downwardly sloping portion 181 thereof.

When transmitter shunting contacts 176 are 75

closed, lever 173 is latched in its extreme counterclockwise position. When lever 173 is in this position, its left-hand end, as viewed in Fig. 4, rocks downwardly into a position of substantial engagement with the upper end of frame 187 of clamp 183.

When it is desired to unlatch function lever 173, key lever 182 is depressed. This causes arm 187 of clamp 183 to be rocked in counterclockwise direction, as viewed in Fig. 4, whereupon downwardly sloping portion 181 of lever 173 is cammed upwardly sufficiently to disengage the shoulder formed in the right-hand end of lever 179 from lever 173 and allow the latter lever to be restored to its solid line position by the action of spring 175.

Although the clamp 183 may be secured to any of the key levers 14, it has been found particularly satisfactory to secure it to the key lever 20 which initiates the generation of the unshift or letters signal combination. According to a widely used system of printing telegraph signal transmission, each signal combination representing a character or a function consists of a permutation code combination of marking and spacing impulses preceded by a start impulse and followed by a stop impulse. In the rest condition of the transmitting apparatus, contacts 42 and 43 identified with bell crank lever 40 operated 25 by cam 66 are closed and represent the stop condition. When the transmitter is operated, these contacts are open, thereby creating a spacing condition of the line which is indicative of the start impulse. The impulses for the particular signal combination are then generated successively and after the last code impulse has been generated the stop impulse contacts 42 and 43 are closed, whereupon the stop impulse is impressed upon the line. The start impulse sets in 30 operation the receiving selector mechanism of printing telegraph receiving unit corresponding to 170 connected to the line, and the stop impulse of marking nature arrests the receiving selector mechanism.

When contacts 176 are closed and function lever 173 is latched, a closed line condition is established so that even though the cam drum 45 rotates, impulses will not be applied to the line. When key lever 182 is operated, it will 45 release the cam drum 45 for a cycle of operation. Until contact springs 176 are opened, the code impulses will not be applied to the line but after the contacts are opened, the impulses will be transmitted. The apparatus is then in a condition for transmission of impulses either from the keyboard transmitter or from the tape transmitter.

Secured to the upper surface of base 12 is a bracket 188 in which there is pivotally mounted 60 a U-shaped member provided with arms 189 and 190 to the former of which is secured a rod 191 adjustable in length by means of an adjusting nut and having its lower end, as viewed in Fig. 4, looped to engage the loop in rod 153 which, as previously described, serves to operate, under certain conditions, T-shaped lever 56 and to remove stop arm 53 from the path of stop lug 54 and cause the rotation of cam drum 45. To arm 191 there is adjustably attached at its free end 65 members 192 and 193 which extend obliquely upwardly and substantially vertically, respectively. Arm 192 lies beneath lever 179 and is adjusted to engage sloping portion 181 of lever 179 upon the operation of its arm 190, which results 70 upon the movement of rod 191 through rod 153

which may be operated by lever 158 and arm 163.

When the apparatus is being operated for the transmission of a message from perforated tape 74 and should the operator at the distant receiving printer desire to reverse the direction of transmission, such operator operates what is customarily referred to as the send-receive break key. Operation of the send-receive break key transmits signal combinations for the operation of function lever 173 to preclude further transmission from the receiving printer with which the contacts 176 are associated. When the function bar 172 is operated to operate function lever 173, a projection thereon engages the upper end of member 193 to rock arms 189 and 190 in a clockwise direction, as viewed in Fig. 4. If the transmitting apparatus is positioned for tape transmission, rod 153 will be in its extreme left-hand position, as viewed in Fig. 4, and stop arm 53 will be held free of stop lug 54 and cam drum 45 will be rotated continuously. When arm 189 is rocked clockwise, as just described, rod 153, through rod 191, will be moved to the right, as viewed in Fig. 4, whereupon lever 158 will be rocked about its pivot from the start to the stop position and T-lever 56 will be restored to its normal position to permit stop arm 53 to be moved to a position where its upper end lies in the path of stop lug 54. When engagement between stop arm 53 and stop lug 54 occurs, collar 49 will be moved along shaft 46 out of engagement with collar 51 and cam drum 45 will be arrested.

When the apparatus is in the condition just described, the operator who operated the send-receive break key may transmit a message to the receiving printer wherein its transmitter was previously being operated for the transmission of a message. Conditioning of the apparatus for resumption of transmission may be accomplished through the depression of key lever 182 if transmission was from the keyboard, or by rocking lever 158 if transmission was from tape 74.

Cessation of transmission from selectable fingers 73 occurs after the last transverse row of code perforations in tape 74 has been presented to the pins on the arm 81 of selectable fingers 73. This condition is evidenced by or indicative of the blank or all-spacing signal. For such a condition there will be obstruction to the movement of all of the selectable fingers 73. An all-blank signal will be transmitted. The receiving printer will respond to such signal in the manner identical with that previously described for the transmission of the send-receive-break signal, except that its operation will be evidenced locally rather than from a distant point.

In response to the all-spacing signal, the selector mechanism of the receiving printer is set to select function bar 172 and through it the operation of function bar 173. Lever 189 is thus operated and through its operation rod 191 is moved backward, as viewed in Fig. 1, whereupon rod 153 is correspondingly actuated to permit stop arm 53 to rotate about its pivot to bring its upper free end in the path of stop lug 54 on collar 49. As previously described, the co-operation between the recited arm of stop arm 53 with stop lug 54 causes disengagement between collars 49 and 51 and the arrestment of cam drum 45. Upon the arrestment of cam drum 45, further signals will not be transmitted unless additional tape is inserted in the tape transmitter or the apparatus is conditioned for

keyboard transmission and the key levers 17 subsequently operated.

The space bar connected to levers 18 may also be operated to move rod 153 to the left, as viewed in Fig. 4, and effect continuous rotation of cam drum 45. Under such circumstances the signal combination identified with the space bar will be transmitted continuously.

Reference is made to copending application 10 of R. A. Lake, Serial No. 303,516, filed November 9, 1939, which discloses a structure similar to the structure disclosed herein and which includes claims directed to those features of the structure which resulted from the sole efforts of the applicant R. A. Lake.

While the apparatus has been disclosed as applied to a particular type of apparatus, it is manifest that the invention is not limited to such specific apparatus but may be embodied in other forms of apparatus without departing from its spirit.

What is claimed is:

1. A telegraph transmitter including a plurality of contacts, permutation bars, key levers for operating said permutation bars in varying combinations, elements controlled by said permutation bars to control the operation of said contacts, means for sensing signal indicia in a strip, means controlled by said sensing means for controlling permutably the operation of said contacts, means for selectively controlling the effectiveness of said sensing means on said controlled means, and means for positioning said permutation bars in an all-spacing position preparatory to transmission from said strip.

2. A telegraph transmitter including a plurality of contacts, permutation bars, key levers for operating said permutation bars in varying combinations, elements controlled by said permutation bars to control the operation of said contacts, a rotary cam drum for operating said contacts successively in accordance with the setting of said elements, means for arresting said cam drum in normal position, means for sensing signal indicia in a strip, means controlled by said sensing means for controlling permutably the operation of said contacts, means for selectively controlling the effectiveness of said sensing means on said control means and for positioning said permutation bars in an all-spacing position preparatory to transmission from said strip, and means operative prior to the transmission from said strip for operating said arresting means whereby said cam drum rotates continuously.

3. In a telegraph transmitter, a set of transmitting contacts, a corresponding set of controllers therefor, a rotary cam operable to operate said controllers in succession, selective devices for modifying the operation of said controllers including key lever controlled elements and strip controlled elements, means for arresting said cam in normal position, means for rendering said key lever and strip controlled elements effective on said controllers, and means operated upon the operation of said last mentioned means to operate said arresting means whereby said cam rotates continuously during transmission from said strip.

4. In a telegraph transmitter, a set of transmitting contacts, a corresponding set of controllers therefor, a rotary cam operable to operate said controllers in succession, selective devices for modifying the operation of said controllers including key lever controlled elements and strip

controlled elements, means for arresting said cam in normal position, means for rendering said key lever and strip controlled elements effective on said controllers, means operated mechanically to control the actuation of cam arresting means, and means operated by the operation of said means for rendering the strip controlled elements effective on said controllers to position all of said key lever controlled elements in a spacing position.

5. A telegraph transmitter including a plurality of contacts, permutation bars, key levers for operating said permutation bars in varying combinations, elements set by said commutation bars to control the operation of said contacts, means for sensing the perforations in a tape, means controlled by said means for determining the operation of said elements, and means for selectively moving said last mentioned means free of and out of operative relation with said elements when said key levers are to be operated.

6. A telegraph transmitter including a plurality of contacts, permutation bars, key levers for operating said permutation bars in varying combinations, elements set by said permutation bars to control the operation of said contacts, means for sensing the perforations in a tape, means controlled by said means for determining the operation of said elements, and means for rendering said last mentioned means effective on said elements and for moving said permutation bars to an all-spacing position preparatory to tape transmission.

7. In a telegraph transmitter, a set of transmitting contacts, a corresponding set of controllers therefor, a rotary cam drum operable to operate said controllers in succession, selective devices for modifying the operation of said controllers including key lever controlled elements and strip controlled elements, means controlling the rotation of said cam drum, means for rendering said key lever selectively effective on said controllers and for moving said strip controlled elements free of said controllers and out of sensing relation with said strip, means for advancing said strip and holding it in its advanced position when said controllers are under the supervision of said strip controlled elements, and means on said cam drum for operating said advancing means cyclically.

8. In a telegraph transmitter, a set of transmitting contacts, a corresponding set of control-

lers therefor, a rotary cam drum operable to operate said controllers in succession, selective devices for modifying the operation of said controllers including key lever controlled elements and strip controlled elements, means controlling the rotation of said cam drum, means for rendering said key lever and strip controlled elements selectively effective on said controllers, means including a ratchet wheel, stepping, and holding

10 pawls for advancing the strip step by step, means on said cam drum for operating said stepping pawl cyclically, and means for withdrawing said stepping and holding pawls from said ratchet wheel whereby the strip may be inserted for 15 transmission.

9. A telegraph transmitter including a plurality of contacts, permutation bars, key levers for operating said permutation bars in varying combinations, elements controlled by said permutation bars to control operation of said contacts, a rotary cam drum for operating said contacts successively in accordance with said elements, means for arresting the cam drum in normal position, means for sensing signal indicia in a strip, 20 means controlled by said sensing means for controlling permutably the operation of said contacts, means for selectively rendering either said permutation bars or said sensing means effective on said contacts, and means operated through 25 30 rendering said sensing means effective to operate said cam drum releasing means whereby said drum rotates continuously for transmission from said strip.

10. A telegraph transmitter including a plurality of contacts, permutation bars, key levers for operating said permutation bars in varying combinations, elements controlled by said permutation bars to control operation of said contacts, a rotary cam drum for operating said contacts successively in accordance with said elements, means for arresting the cam drum in normal position, means for sensing signal indicia in a strip, means controlled by said sensing means for controlling permutably the operation of said 40 contacts, means for selectively rendering either said permutation bars or said sensing means effective on said contacts, and means operated independently of said strip for actuating said cam drum releasing means whereby said drum rotates 45 continuously for transmission from said strip.

ALBERT H. REIBER.
